BOAT-HANDLING APPARATUS AND PROCESS
William A. Keene and James C. Carroll, Bartlesville,
Okla., assignors to Phillips Petroleum Company, a cor-
poration of Delaware

Filed July 13, 1964, Ser. No. 382,157
8 Claims. (Cl. 214—1)

This invention relates to apparatus, and to processes of operating said apparatus, for handling boats. In one aspect, it relates to taking boats out of the water they are floating in and storing them on land during periods they are not being used, and also taking them from storage on land and floating them in the water when they are to be used. In another aspect, it relates to handling small boats very carefully, without any appreciable chance of damage to their hulls, rudders, propellers or paint, with maximum speed, minimum labor, and in such an efficient manner as to attract the owners of such boats and make them want to pay for such handling and storage services at a large marina. A marina generally comprises a gasoline service station on land adjacent a body of water for servicing small power boats, generally boats from about 12 to 30 feet long which have internal combustion engines, some inboard and some outboard, said boats weighing from about 500 to 10,000 pounds. The word "land" in this specification and claims is intended to include wharves, piers and other structures which may be surrounded by or extend out into the water, but having floors or decks above water level, and to also include floors or pavements laid on or positioned above the surface of the ground.

In the prior art, there have been many cheap marinas built, with dilapidated wharves and makeshift marine ways and winches to haul boats out of the water in a crude manner on skids or wheeled carts. Such treatment of a boat is very hard on its paint, hull, propellers or other parts. At present, with many potential customers owning boats worth thousands of dollars and having plastic hulls of such materials as glass fiber-reinforced polyesters, or wooden hulls of mahogany or teak-wood with a very high finish, these owners do not want their precious boat damaged by crude attempts to remove it from the water.

The present invention overcomes these difficulties of the prior art by lifting the boat out of the water on an air-inflated bag, moving it about on land on a cushion of flowing air, and storing it on solid, contour-fitting, supporting chocks onto which it is gently lowered by deflating said bag. The same gentle care is employed in removing it from said chocks by inflating a bag under it, moving it supported on said bag on a cushion of flowing air, and lowering it gently into the water. Aside from the fees that customers gladly pay for such superior service, this invention makes the adjacent gasoline service station (not shown) more attractive and brings it more customers for fuel, repairs, meals and other services.

One object of this invention is to provide a novel combination of apparatus for and novel processes for handling boats in and out of the water in a superior manner with very little danger of doing any damage to their finish or to their hulls or equipment.

Other objects are to provide means and processes suitable for moving boats on inflated air cushions and on cushions of flowing air.

This apparatus is a basic part of a low cost system for handling boats into and out of storage or repair areas, as in marinas. The apparatus comprises an air pallet. This pallet utilizes the ground effect principle of air flotation for easy movement across paved areas. The top of the air pallet is equipped with two inflatable rub-

2

ber bags or pneumatic chocks. The inflatable pneumatic chocks serve as a jack to raise the boat on the pallet, also, due to their shape and conformity, they support the hull at numerous locations and hold the boat upright.

- 5   Advantages of the system include the following:
      (1) Low original cost of equipment and pavement.
      (2) Ability to hand move the boat in any direction to maneuver it in tight areas, such as between columns, posts, or other craft.
10   (3) Little or no danger of the hull being scratched or damaged by mechanical handling devices.
      (4) A single system fits all boats between 12 feet and 30 feet long.
15   (5) The entire hull is supported while the boat is being lifted from the water and handled.
      (6) The contour blocks or storage chocks are applied after the hull is entirely visible; thus they can be located at the proper support points on the hull as marked or recommended by the boat manufacturer.
20   (7) The system requires little head room in excess of the over-all boat height.
      (8) It is known that the basic economic success of a marina depends upon the number of craft stored. The maneuverability of this system allows for optimum use of the available space. This is of vital interest to marina operators and designers.

Numerous other objects and advantages will be apparent to those skilled in the art, upon reading the accompanying specification and claims.

- 30   In the drawing:
      FIGURE 1 is an elevational view, with parts broken away, showing a boat-handling apparatus, system and process embodying the present invention, with prior positions of boat 11 shown in broken lines.

35   FIGURE 2 is a view smaller to FIGURE 1 showing a portion of the same at a later stage in the process of taking a boat out of the water, or an earlier stage in the process of putting a boat back into the water.

40   FIGURE 3 is a cross-sectional view taken along the line 3—3 of FIGURE 2 looking in the direction indicated.

FIGURE 4 is an elevational view of the same boat in storage, resting on the hull-contour fitting solid chocks.

45   FIGURE 5 is a cross-sectional view taken along the line 5—5 of FIGURE 4 looking in the direction indicated.

FIGURE 6 is a perspective view of an air-in-pallet which is shown in use in FIGURES 1 to 4.

50   FIGURE 7 is a cross-sectional view of FIGURE 6 taken along the line 7—7 looking in the direction indicated.

FIGURE 8 is an elevational view of a modified means for handling the boat at about the same point in the process as shown in FIGURE 2.

55   FIGURE 9 is a cross-sectional view similar to FIGURE 7 but showing the use of an air-in-floor modification which may be used in the practice of the invention in place of the air-in-pallet modification of FIGURE 7.

60   In FIGURE 1 a boat, generally designated as 11, is shown in three successive positions in the process of being removed from a body of water 12 and being stored on land 13, which land in FIGURE 1 comprises a pier having a floor or deck 14, supporting on piling 16. Due to differences in the geology in different shorelines, land 13 may be in many different forms, including all types of geological rock formations, or sand bars or mud banks (none of which are shown), with or without man-made structures thereon. It is very rare where the ground extends near enough to the deep water and has a surface

thereon smooth enough to permit the operation of air-in-pallets on its surface, so generally land 13 will be provided with a floor 14, or asphalt, cement or other suitable paving to make the same smooth enough for air pallet 46 operation. However, the present invention is concerned with land and with water, land being distinguished by having a dry surface above the surface of the water; and because of the wide difference in geology from place to place and what man-made construction this geology requires to obtain a relatively smooth surface, it is believed impractical to define the term land any more specifically in the claims.

In FIGURE 1 there is a crane generally designated as 17 disposed so as to cover part of the land 13 and water 12. A crane is any hoisting machine having the added capacity of moving a load in a horizontal or lateral direction. While a traveling crane is shown, obviously the crane could be of any other type, such as a jib crane, derrick crane, bridge crane, or pillar crane, and still practice the present invention.

As cranes, per se, are old and as any type of crane will operate, it is not believed necessary to go into great detail about crane 17, except to state that, as shown, it comprises a track 18 extending over water 12 and land 13 on which hoists 19 and 21 travel supported by wheels 22. It is preferred to have an adjustable distance between hoists 19 and 21 which may be obtained by using a telescopic tube 23 and rod 24 which can be fastened at any desired distance by set screw 26. There is a continuous traversing cable 27 running over drive pulley 28 driven by motor 29 at one end of track 18 and over a free pulley 31 at the other end of the track. As motor 29 is reversible, the hoists 19 and 20 can be pulled from one end of track 18 to the other, as shown, and any slack in line 27 can be passed over pulley 31 on hoist 19 to form loop 32 connected to collar 33 secured in position on cable 27 by set screw 34. Each of hoists 19 and 21 is provided with a hoist motor 36 and 37 driving a conventional winch (not shown) for raising and lowering slings 38 and 39, respectively. As all of this crane mechanism is old, it is believed unnecessary to show the wiring for motors 29, 36 and 37 or how they are connected through electrical conduit 41 with control box 42, it being obvious that handle 43 may start, stop or reverse motor 29 while handle 44 is rotated in a similar manner to start, stop and reverse both motors 36 and 37 at the same time.

The boat 11 is originally floated on the surface of water 12 as shown in the furthest left broken line position. Slings 38 and 39 are lowered, connected to and supporting a platform or air pallet 46 which in turn supports a submerged, deflated, pneumatic bag or chock 47. Pallet 46 and bag 47 are passed under boat 11. It is desirable to do this while bag 47 is deflated, because then it need not be lowered so deep, and because when inflated bag 47 has considerable buoyancy making it hard to handle under water. Nevertheless, bag 47 may be inflated and placed under floating boat 11 by merely lowering it a little deeper than shown, and it is desired to cover both these alternative ways of operating. If lowered in inflated form (not shown), boat 11 may then be picked out of the water simply by hoisting slings 38 and 39. However, if placed under boat 11 with bag 47 in deflated form, the bag should then be inflated by pumping air under pressure in at connection 48 until boat 11 is supported thereon, and then hoisting slings 38 and 39 into the position shown in the right-hand broken line position of boat 11 in the center of FIGURE 1. Once the bottom of pallet 46 is hoisted to a greater elevation than that of deck 14 by motors 36 and 37, then the suspended platform 46 and supported bag 47 and boat 11 supported therein can be hauled by motor 29 to the right-hand solid line position of boat 11 over the floor portion 14 of land 13 and lowered until pallet 46 sits on the surface of deck 14.

At this time, or at any time later in the process before bag 47 is deflated, solid support chocks 49 and 51 may be secured, preferably in form-fitting contour with the hull 52 of boat 11, preferably fore and aft of bag 47, by any suitable means such as straps 53 and clamps 54 of conventional construction. While it is preferred to attach chocks or contour blocks 49 and 51 to boat 11 by securing means 53, it is unnecessary to do so as chocks 49 and 51 can be brought up after pallet 46 has positioned the boat 11 in its final storage position and can be placed under boat 11 without using straps 53, and then lowering the boat 11 onto said chocks by means of deflating bag 47 at air connection 48.

FIGURE 2 continues the operation from the solid line position of boat 11 in FIGURE 1 by removing slings 38 and 39 from boat 11 and removing air fitting 48 and extension line 56 from air fitting 57. Both air fittings 48 and 57 contain automobile tire-type spring-pressed check valves which normally allow air to pass into bags 47 but will not allow air to come out unless the valve is depressed by hand, or tool. As these valves are common in all automobile tires today, it is unnecessary to illustrate them.

At this point an air hose 58 is attached to blow air into air pallet 46. As soon as a sufficient amount of air at a sufficient pressure and at a sufficient rate passes through hose 58, pallet 46 supporting bag 47 and boat 11 will rise off the ground and hover at least a fraction of an inch above the ground, utilizing the ground effect principle of air flotation for easy movement across smooth areas. As long as air continues to be pumped in hose 58 at a suitable rate, boat 11 may be pushed by hand, as a force of less than 10 pounds will move well over a ton of load on an air pallet with only an air pressure of 3 to 5 pounds per square inch gauge inside the pallet. One advantage of the air pallet 46 over a dolly having casters (not shown) is that it may be moved instantly in any direction whatever without waiting for the casters to turn, or applying force to turn the casters. Also, the air pallet will support loads greater than the casters can stand and will not make marks on the floor or tear up the floor as heavily-loaded casters will do.

Assuming that solid supporting chocks 49 and 51 have been secured in place with straps 53 and clamps 54, whenever the boat is positioned where it is to be stored, turning off the air coming through hose 58 will lower the boat into a fixed position on the pallet 46, whereupon the air can be let out of bag 47 by depressing valve 57 and the boat will be lowered onto supports 49 and 51. Bag 47 being further deflated, air pallet 46 and bag 47 can be easily pulled out from under the boat 11. While this movement can be aided by pumping in more air through pipe 58, this is not generally necessary as pallet 46 and bag 47 are light and can be dragged by hand out from under the boat without any air lift. However, continued air lift is preferred.

In some instances it may not be desirable to attach chocks 49 and 51 with straps 53, but they can be positioned under the boat 11 after it has been removed to its final position and before deflating bag 47.

FIGURE 3, being a cross-sectional view of FIGURE 2, is believed to need no further explanation. It is noted, however, that instead of a single bag 47 a pair of bags 47' may be employed on air pallet 46 to support boat 11, in which case there must be an air valve 57 for each of the bags.

FIGURE 4 is merely a view of boat 11 sitting in storage on chocks 49 and 51 after bag 47 and pallet 46 have been removed, and FIGURE 5 is a cross-sectional view of the same, so no further description is necessary. These chocks are preferably made to fit the contour of the hull of the particular boat being stored and can be provided with a layer of foamed rubber or felt 58 next to the hull of the boat.

FIGURES 6 and 7 show the air-in-pallet modification of the ground effect air lift system. Compressed air at a pressure of about 5 pounds per square inch gauge is forced into fitting 59 at a rate sufficient to maintain this pressure in plenum chamber 61 of FIGURE 7, this air being preferably distributed to said plenum chamber through a suitable manifold 62. While many alternative constructions can be employed, in FIGURE 7 the pallet has a metal body comprising sides 63, top 64 and bottom 66, with zigzag reinforcing 67 provided with opening 68 allowing air to move in plenum chamber 61 throughout the entire body. At suitable intervals as shown, there are provided air nozzles 69 through which the air blows against the floor 14 with sufficient force to raise the pallet 46 and supported boat 11 off of floor 14 a fraction of an inch on a flowing blanket of air. In order to reduce wear and friction, the top of pallet 46 may be provided with a plywood layer 71 and the bottom is provided with a resilient pad 72 of natural or synthetic rubber, or other suitable resilient material, preferably covered with a scuff-resistant coating 73 of either a suitable laminated plastic, such as polyethylene or polyester, or a layer of metal.

While as pointed out above it is easy for one man to push a large boat around on this air pallet, in order to operate in the most efficient manner with a minimum of human labor, in FIGURE 8 it is preferable to have an automobile tractor 74. Such tractor 74 is well known, being used as a fork lift truck and the like, and may be purchased on the open market, and therefore a detailed description is believed unnecessary. Tractor 74 is provided with a motor 76 which may be an internal combustion engine, or electric motor with a battery, and this motor may be used to drive wheels 77 in the manner of any automobile. If desired, instead of having air hose 58 come from a stationary air compressor (not shown), a portable air blower 78 may be mounted on tractor 74 and driven by motor 76 (or an auxiliary motor not shown), and hose 58 may be supported from a boom 79 on tractor 74. There are numerous ways in which tractor 74 may be connected to air pallet 46 in order to push or pull the same, such as by boom 81, balls 82 mounted on pallet 46 and socket connection 83 mounted on boom 81 and adapted to be clamped around ball 82. As such connections are quite old on automobiles and trailers for automobiles, it is believed unnecessary to go into specific details. In FIGURE 9 is shown a second modification of the ground effect air lift principle in which a pallet 85 is supported on a moving blanket of air a fraction of an inch above floor 84 by means of air coming through pipes 86 and 87 in floor 84 to a series of outlets 88 and 89 spaced in floor 84. Each of outlets 88 and 89 is provided with a ball check valve 91 which is pressed upward to seal outlet 88 by helical compression spring 92 at all times except when the lower layer 73 of pallet 85 contacts ball 91 as the outlet 89 depresses the same and allows air to escape from pipe 87 around ball 91 and out between layer 73 and floor 84 supporting the pallet 85 on a moving blanket of air. It should be noted that pallet 85 appears the same as pallet 46 of FIGURE 7 and can be exactly the same. However, it is possible to add a closed valve (not shown) to pipe 59 of FIGURE 6 and/or to eliminate air nozzles 69 of FIGURE 7 and have surface 73 unbroken and flat (not shown), although if valve balls 91 are close enough together as shown, pallet 46 will operate the same as 85 over them, which is preferred.

When the system of FIGURE 9 is employed, a stationary air compressor (not shown) supplies air to pipes 86 and 87 and it is unnecessary for tractor 74 of FIGURE 8 to have blower 78 or air hose 58 because the pallet is being supported by air being blown through the floor. Careful consideration should be given as to whether the system of FIGURE 7 or that of FIGURE 9 is more

suitable for the particular marina that is being constructed. Unless there is some reason why the system of FIGURE 9 is preferable, it is believed the system of FIGURE 7 is the one to be chosen, as it is more versatile, cheaper to install and operate, and requires less maintenance. However, FIGURE 9 obviously requires less equipment and less hauling around of air hose 58, which is eliminated.

Obviously, the launching of the boat 11 from its position on chocks 49, shown in FIGURE 5, to its position in the water 12, as shown in broken lines at the left side of FIGURE 1, is a mere reversal of the procedure described above. Pallet 46 with air bags 47 deflated is inserted under the boat 11 between chocks 49 and 51 and air bags 47 are then inflated with compressed air through air valves 57. As bags 47 inflate, boat 11 is gently lifted until chocks 49 and 51 leave the floor 14. Obviously, at any time after the inflating bags 47 engage boat 11, chocks 49 and 51 may be detached by undoing straps 53 from catches 54 if, in fact, straps 53 and clamps 54 were ever used. Air is then pumped through hose 58 into pallet 46, or if pallet 83 of FIGURE 9 is being employed, air is pumped into pipes 86 and 87, until whichever pallet 46 or 83 is being used floats on a blanket of air by ground effect. At this time pallet 46 or 83 and supported boat 11 may be pushed by hand or by tractor 74, under crane 17, and slings 38 and 39 attached to balls 82. Air hose 58 (if used) is disconnected and handle 44 is rotated to actuate motors 36 and 37 to hoist pallet 46 and boat 11 off of the floor 14 a suitable distance, whereupon motors 36 and 37 are shut off and handle 43 is employed to actuate motor 29 to haul boat 11 to the left out over water 12 whereupon motor 29 is stopped and motors 36 and 37 are actuated to lower boat 11 into water 12. At this point, pallet 46 and air bag 47 may be lowered sufficiently so that boat 11 floats out of them, or they can be lowered so that boat 11 is ready to float and then bag 47 is deflated, freeing boat 11. While specific apparatus and specific process steps have been described for purposes of illustration, it is to be understood that the invention is not limited thereto. Obviously, whether pallet 46 and air bag 47 can be lowered in the water with the bag inflated, or not, depends on whether the submerged weight of the pallet is sufficient to overcome the buoyancy of the inflated bag. If this weight is not sufficient, the bag can always be deflated so that the combined pallet, supports and bag will sink in the water.

Having described our invention, we claim:

1. The process of removing a boat from water and storing said boat on land, said water and land both being covered in part by a crane, comprising the steps of:
suspending a platform by slings from said crane;
placing the suspended platform under said boat while said boat floats on said water;
positioning an inflatable bag between said boat and said platform;
inflating said bag to raise said boat on said platform;
hoisting said platform, supported bag and supported boat from said water with said crane;
moving said hoisted platform, bag and boat over a portion of said land covered by said crane;
lowering said platform, bag and boat onto said land;
disconnecting said slings from said platform;
injecting air between said land and said platform in sufficient amount and at sufficient pressure to elevate said platform on a cushion of flowing air;
moving said platform, supported inflated bag and supported boat to a desired storage point while elevated on said cushion of air;
positioning solid supporting chocks between said land and said boat; and
deflating said bag and thereby lowering said boat on said chocks for storage.

2. The process of removing a boat from water and storing said boat on land, said water and land both being covered in part by a crane, comprising the steps of:
- suspending a platform by slings from said crane;
placing the suspended platform under said boat while 5
said boat floats on said water;
positioning an inflated bag between said boat and said platform;
hoisting said platform, supported bag and supported boat from said water with said crane;
moving said hoisted platform, bag and boat over a portion 10
of said land covered by said crane;
lowering said platform, bag and boat onto said land;
disconnecting said slings from said platform;
injecting air between said land and said platform in 15
sufficient amount and at sufficient pressure to elevate said platform on a cushion of flowing air;
moving said platform, supported inflated bag and supported boat to a desired storage point while elevated 20
on said cushion of air;
positioning solid supporting blocks between said land and said boat; and
deflating said bag and thereby lowering said boat on said chocks for storage.
3. The process of removing a boat from solid supporting chocks on land and floating said boat in water, said water and land both being covered in part by a crane, comprising the steps of:
- placing a platform under said boat;
positioning an inflatable bag between said platform and 30
boat;
inflating said bag and raising said boat off of said chocks;
injecting air between said land and said platform in 35
sufficient amount and at sufficient pressure to elevate said platform on a cushion of flowing air;
moving said platform, supported inflated bag and supported boat to a position on land under said crane while elevated on said cushion of air;
attaching said platform to said crane by slings;
hoisting said platform, supported bag and supported 40
boat from said land;
moving said platform, bag and boat over said water; and
lowering said platform, bag and boat into said water into a position where said boat will float when said bag is deflated and deflating said bag so that said boat floats.
4. The process of removing a boat from solid supporting chocks on land and floating said boat in water, said water and land both being covered in part by a crane, comprising the steps of:
- placing a platform under said boat;
positioning an inflatable bag between said platform and 45
boat;
inflating said bag and raising said boat off of said chocks;
injecting air between said land and said platform in sufficient amount and at sufficient pressure to elevate said platform on a cushion of flowing air;

- moving said platform, supported inflated bag and supported boat to a position on land under said crane while elevated on said cushion of air;
attaching said platform to said crane by slings;
hoisting said platform, supported bag and supported boat from said land;
moving said platform, bag and boat over said water; and
lowering said platform, bag and boat into said water into a position where said boat will float.
5. A system for storing boats on land adjacent a body of water comprising in combination:
- a crane movable over a portion of said land and a portion of said water;
means comprising a platform and an inflatable bag positioned on said platform adapted to support the hull of said boat thereon;
sling means adapted to connect said platform to said crane when said crane is used to hoist said boat;
means to inject air under sufficient pressure, in sufficient quantity and at a sufficient rate to raise said platform off of said land on a cushion of flowing air when said platform is to be moved on land;
solid supporting blocks adapted to support the hull of said boat on land at an elevation sufficient to allow the removal and insertion of said platform and inflatable bag from under said boat when said bag is deflated and insufficient for said blocks to reach the ground when said bag is inflated;
means to inflate said bag when desired; and
means to deflate said bag when desired.
6. The combination of claim 5 in which the means to inject air to raise said platform off of said land comprises an air compressor having a discharge conduit, a plenum chamber in said platform, and spaced holes in the bottom of said platform connected to said plenum chamber, with said discharge conduit connected to said plenum chamber.
7. The combination of claim 6 in which there is provided an automobile having an engine, means for connecting said automobile to said platform, and said air compressor is mounted on said automobile and driven by said engine.
8. The combination of claim 5 in which the means to inject air to raise said platform off of said land comprises an air compressor having a discharge conduit, a manifold of pipes in the land connected to said discharge conduit, said pipes having a series of spaced openings, and an outwardly-closing ball check valve controlling flow of air through each opening positioned so as to be depressed and opened by said platform.
